CLAIM

The ornamental design for an adjustable squirrel baffle, as shown and described.

DESCRIPTION

FIG. 1 is a top, front and right side perspective view of an adjustable squirrel baffle, showing my new design;

FIG. 2 is a bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is another perspective view of the adjustable squirrel baffle shown in its open state;

FIG. 10 is a perspective of the adjustable squirrel baffle shown in its use state;

FIG. 11 is another perspective of the adjustable squirrel baffle shown in its use state;

FIG. 12 is an enlarged view of portion 12 in FIG. 1;

FIG. 13 is an enlarged view of portion 13 in FIG. 1;

FIG. 14 is an enlarged view of portion 14 in FIG. 2;

FIG. 15 is an enlarged view of portion 15 in FIG. 2;

FIG. 16 is an enlarged view of portion 16 in FIG. 3; and,

FIG. 17 is an enlarged view of portion 17 in FIG. 9.

The broken lines in the figures depict environmental subject matters and form no part of the claimed design. The dash-dot-dash broken lines define the boundary of enlarged views and form no part of the claimed design.
